UNITED STATES PATENT OFFICE.

RAY STEARNS AND WILLIAM S. H. HAMILTON, OF SCHENECTADY, NEW YORK, ASSIGNEES TO GENERAL ELECTRIC COMPANY, A CORPORATION OF NEW YORK.

SYSTEM OF CONTROL.

1,267,817.

Specification of Letters Patent. Patented May 28, 1918.

Application filed March 24, 1916. Serial No. 86,332.

To all whom it may concern:

Be it known that we, RAY STEARNS and WILLIAM S. H. HAMILTON, citizens of the United States, residing at Schenectady, county of Schenectady, State of New York, have invented certain new and useful Improvements in Systems of Control, of which the following is a specification.

Our invention relates to a system of control for electric motors, and is particularly directed to an improved system of control for traction motors which are arranged for regenerative braking.

Where series traction motors are employed for regenerative braking, it has been found desirable to provide auxiliary sources of current which shall be connected across the series field windings of the motors in order to stabilize and readily control their operation as generators, and to provide two controllers one of which shall determine the interconnection of the motors and their starting resistances during motoring, while the other shall determine the connection of the auxiliary sources, as well as the effect thereof when it is desired to use the motors as generators for braking.

It is the main object of our invention to so control the relative operation of these two controllers, and certain auxiliary apparatus to be hereinafter described, that the system as a whole will be operated in a safe and effective manner, and improper and dangerous conditions of operation will be prevented.

To this end, we have so interlocked the motoring and braking controllers that the regenerative connections may be established only when the motoring controller occupies certain predetermined positions, and so that after the regenerative connections have been established the motoring controller may be moved to change the connections of the motor circuit only when the braking controller occupies a certain predetermined position. Provision is also made whereby the regenerative connections, after they have once been established, can only be disconnected by moving the motoring controller to its off position, and whereby the movement of the motoring controller from a high speed position to a low speed position opens the main line circuit before any change in the motor connections is made and prevents the circuits from being reestablished until after

both controllers have been returned to their off positions. The reasons which underlie our invention and the means by which the above results are accomplished will be pointed out in detail in the accompanying 60 specification.

Considering our invention in its broadest aspect the motoring and braking controllers in a system of control embodying our invention may be of any desired form and may 65 operate either to control the various circuits directly or indirectly. We have chosen to illustrate our invention in connection with a locomotive equipment designed to handle heavy electric locomotives and employing 70 the now well known form of distant control in which the switches which directly control the motor circuits are independently operated under the control of a master controller or controllers. 75

Our invention also comprises certain novel features in connection with the transfer of the motor connections from series to parallel during regenerative braking as well as novel features in the construction and arrangement of the motoring and braking controllers and the auxiliary switches used in conjunction therewith, all of which will be hereinafter described in detail.

Our invention will be more readily understood by reference to the accompanying drawing, in which Figure 1 is a diagram showing the power apparatus employed in an equipment for an electric locomotive, together with certain special elements of the control apparatus; Fig. 2 is a diagram of the control circuits, together with the development of both controller drums; Fig. 3 is a diagram of the power circuits, showing the relation of the contactor contacts to the power apparatus; Fig. 4 is a table showing which contacts are closed at the various steps of the main controller; Fig. 5 is a diagrammatic representation of the contacts of the series parallel switch, together with the 95 cams used to operate the same; Figs. 6 to 28 are diagrams of the resulting circuits at various positions of the main controller; Fig. 29 is a side elevation of our assembled controllers; Fig. 30 is a top view of the same; 105 Fig. 31 is a fragmental front elevation of the central portion of the assembled controllers with the covers removed; Fig. 32 is a top view of the main controller with part of the cover thereof broken away; Fig. 110

33 is a section on the line 33—33 of Fig. 31, and shows a top view of the main controller drum and the contact fingers; Fig. 34 is a fragmental section through the controller drum on the line 34—34 of Fig. 33; Fig. 35 is a section on the line 35—35 of Fig. 31, and it shows the auxiliary break; Fig. 36 is a section on the line 36—36 of Fig. 31; and Fig. 37 is a section on the line 37—37 of Fig. 31, the latter two figures showing the cams and pawls by means of which the handles of the two controllers are mechanically interlocked; Fig. 38 is a diagrammatic view in perspective, in which is shown the interrelation of the parts illustrated in Figs. 35, 36, and 37; Fig. 39 is a view, partly in section, showing the controller handles and their latches; Fig. 40 is a view of the engine end of the series parallel switch with parts removed and a portion broken away, and Fig. 41 a view of the opposite end thereof; Fig. 42 is a section on the line 42—42 of Fig. 41 through the cut-out handles; Fig. 43 is a front elevation of said switch; Figs. 44 to 50, inclusive, are sections through the operating shaft taken on the corresponding section lines in Fig. 43; Fig. 51 is a section on the line 51—51 of Fig. 43, showing a pair of contacts; Fig. 52 is a side elevation of the reverser; Fig. 53 is a section on the line 53—53 of Fig. 52; Fig. 54 is a section on the line 54—54 of Fig. 52; Fig. 55 is a fragmentary view of one end of the interlocking contacts; Fig. 56 is a diagram showing the circuit connections of the reverser with the motors.

The particular system of control which is illustrated in the drawings and to which we have applied our invention comprises:

40 First, a distant or master control system for a plurality of series traction motors, or groups of such motors, of a form now well known, comprising switches for cutting in and out resistance in the motor circuit and 45 for changing the connections of the motors or groups of motors from series to parallel and shunting the fields in the final position of the controller;

50 And second, auxiliary sources of supply for exciting the series fields of the motors to cause them to return energy to line together with an automatic system for controlling the excitation of the motors, which in itself forms no part of our present invention and is covered by an application of 55 William S. H. Hamilton Serial No. 86,356, filed March 24, 1916 and assigned to the same assignee as this present application.

The switches associated with the master 60 motoring controller comprise a set of line switches and resistance controlling switches 71 to 80 inclusive and 82 to 86 inclusive, and 88, operated by electromagnets the circuits of which are completed at the master controller, and switches 90 to 97 inclusive for

completing the series connections and the parallel connections of the motors and for controlling the transition from series to parallel and vice versa, which in the arrangement illustrated are actuated by a common 70 operating member actuated by pneumatic pressure under the control of two electromagnets 125^a and 126^a, these electromagnets being energized, the one when the master controller of the motoring system is moved 75 into its series position and the other when it is moved into its multiple positions. The reversing switch in the system illustrated also comprises a separate switch actuated by pneumatic pressure under the control of two 80 electromagnets, 121^a and 122^a the circuits of these magnets being controlled by a master reversing switch, R.

85 Switches 81 and 87 are employed for completing circuits between suitable exciter armatures and the fields of the traction motors so as to produce the excitation necessary for regenerative braking. The operation of these switches is controlled by the master controller for regenerative braking and this 90 same controller also governs, in conjunction with the automatic control above referred to, the excitation of the exciter which furnishes current to the fields of the motors during regenerative braking. 95

The features constituting our present invention and the operation of the system as a whole will be best understood by a consideration of its several parts.

POWER APPARATUS AND SPECIAL RELAYS.

100 Referring first to Fig. 1, the power apparatus employed for a locomotive to which our invention is applied includes traction motors A and B, whose field windings A^f and B^f are combined in groups of two, for 105 reasons to be later explained. So far as our invention is concerned, it is immaterial whether the motor, designated as A or B, comprises one or a group of motors. A motor-generator set will also be commonly employed in order to provide current at a reduced voltage for the control apparatus and for other purposes. This will comprise a 110 driving motor M, which is here shown as being provided with two commutators arranged in series in order to adapt the same to a high trolley voltage, a control generator C is utilized to supply current at a reduced 115 voltage to the control apparatus, and an exciter E, here shown as provided with two armature circuits E^a and E^b, providing the auxiliary source of current adapted to be 120 connected across the fields of the motors in order to stabilize their operation as generators. This motor-generator set will commonly include a fan F, which may be used 125 for ventilating purposes. In this figure, we have also shown an overload relay having a trip coil 89^a, a high voltage relay having a 130

trip coil 100a, a braking relay 101a, a motoring relay 102a, a transfer relay 103a, reversing relays 104a and 105a, and a contact-making ammeter 109. None of these relays has contacts directly in the power circuits, and their only function is to electrically open and close certain of the control circuits. For the purpose of automatically controlling the shunt field winding 130 of the exciter E, we provide a motor-operated rheostat 118, which includes a driving motor 110, which when in operation runs continuously in the direction indicated by the arrow, and a rheostat arm 114 driven by beveled gears in one direction or the other, accordingly as one or the other of the clutch coils 111 and 112 is energized. The movement of this arm operates to short-circuit more or less of the resistance 113 included in series with the shunt field winding 130. The exciter E is also provided with a series field winding 131, which is traversed by the current in the motors A and B during the series operation and by the current in the motors A during the parallel operation. The power supply is received through a trolley T and, passing through the winding or windings 89a (see Fig. 3) of the overload relay, is delivered to the armatures A and B of the traction motors, and then passes through the field windings Af and Bf and the series field winding 131 to ground. These field windings are placed on the ground side of the armatures in order to reduce the voltage strain upon their insulation. We have in this figure also shown the development of the rotating cylinder of the braking controller 300, but for the sake of simplicity we have omitted the motoring controller 200 by means of which the relative connections of the traction motors and their starting resistances may be varied.

THE CONTROL CIRCUITS AND CONTROL APPARATUS.

In Fig. 2, however, we have shown the development of the rotating cylinders of both the braking controller 300 and the motoring controller 200, and in this figure we have restricted the circuits shown to the control circuits for the various electromagnetic switches or contactors. Considering first the motoring controller 200, it will be seen that the moving contacts, here shown in development, are capable of movement with reference to fixed contacts which are connected to control wires numbered 150 to 163, and of being placed in any one of various positions, designated by dotted lines lettered *a* to *p*. Current of suitable voltage is supplied to the control wire 150 through the contacts 331 of an auxiliary break, to be later described. Inasmuch as all the contact bars upon the rotating drum are interconnected, this current will, at any particu-

lar position of the controller, pass out over corresponding control wires and energize the coils which may be in circuit therewith. In all operating positions of the main controller, current will pass out over the control wire 151, to the reverser R, and to a contact on the drum of the braking controller 300. This reverser is provided with a manually movable contact 261, capable of movement in two positions by means of which either the coil 121_y or 122_z will be energized, and, in a manner to be later described, cause the movement of the reverser to the position corresponding to forward or reverse movement of the vehicle, respectively. The reverser is provided with interlocking contacts 122 and 123, mechanically attached to the moving parts thereof in such a manner that these contacts coöperate with fixed contacts in either of the positions of the reverser to thereby energize control wire 170. As before described, a control current is supplied to the moving contacts of the braking controller 300 by means of a wire 151. These contacts are all interconnected and are capable of movement with relation to fixed contacts whereby control wires 180 to 187 may be energized, according to which one of the several positions *q* to *x* it assumes.

In Fig. 3, we have made a diagram showing the traction motors A and B, traction motor fields Af and Bf, the starting resistances S, the exciter armatures Ea and Eb, and the contacts of the various switches by means of which the relative interconnection of these elements is altered. Certain of these switches, numbered 71 to 88, inclusive, are electromagnetically - operated contacts, or contactors, while others of them, numbered 90 to 97, inclusive, are cam-operated contacts, forming part of a piece of apparatus known as the series-parallel switch, which will be later described. It should be here noted that for each pair of contacts of the various contactors, or switches, 71 to 88, there is shown, in Fig. 2, a corresponding operating coil, designated by the numerals 71a to 88a, inclusive, and that where electrical interlocking switches are provided upon any one of these contactors, these switches are designated by applying the subscripts *b*, *c*, *d*, *e*, etc., to the corresponding number by means of which the contactor contacts are designated. All interlocking switches in Fig. 2 which are associated with electromagnetic contactors are there shown in the position which they will assume when the operating coils of said contactors are de-energized. Upon the energization of a contactor, the associated interlocks will be moved toward the top of the sheet. Certain other interlocking switches, 115, 116, and 117, which are mechanically related to the moving arm 114 of the motor-operated rheostat 118, are shown in the position which

they will occupy when the said arm is moved to the extreme right (see Fig. 1), so as to include all of the resistance 113 in the circuit of the shunt field 130 of the exciter E. 5 Certain other interlocks, numbered 125b, 126b, 127b, 127c, 127d, and 127e, are mechanically connected to the moving parts of the series-parallel switch, and are here shown in the position they will assume when said switch is in the series position (see Fig. 10 43) designated in Fig. 5 by the letter T1. Certain other interlocks, designated by the numerals 89b, 89c, 89d, and 100b, are shown in the position which they will occupy when 15 the overload relay and the high voltage relay are in their set or undisturbed position. When these relays are tripped the interlocks will open.

20 THE RESULTING CONNECTIONS.

Accelerating to series position.

Let us now consider the resulting connections when the main controller 200 is moved 25 to the position *a*, (the auxiliary break 381 being thereby closed, as will later appear). Due to the energization of control wire 151, and through the braking controller of the control wire 180, coil 102c of the motoring 30 relay will be energized, thereby closing its contacts 102b and 102c. Supposing that the movable element 261 of the reverser R has been set in the forward position, then the movable contacts 122 and 123 will be in the 35 position *y* as shown, and control wire 170 will be energized through the contact 123. This will, assuming that the overload relay 89 is in its set position, cause the energization of control wire 171 and, consequently, 40 of the coils 71a and 74a. At the same time, energization of the control wire 152 will energize the coil 125a, by means of which the series-parallel switch will be caused to move to the full series position indicated 45 by T1 (Fig. 5), and the cam-operated contacts 92, 94, and 96 closed. Contacts 91 are closed at all times except when cutting out a pair of motors. The coils 89r and 100r will be also energized from this wire, therefore 50 by resetting the overload relay and the high voltage relay in case these have been tripped. At the same time, coils 73a and 82a will be energized from this wire, and the connections obtained will be seen by reference to 55 Fig. 6, which corresponds to position *a* of the controller. The four motors are connected in series with one another and with all of the elements of the starting resistance S. The resulting connections obtained by 60 further movement of the controller through the positions *b* to *h* are illustrated in Figs. 7 to 13. In Figs. 7 to 11, we have only illustrated the starting resistances S, for the reason that the only changes consist in cutting 65 out various sections of these resistances by

short-circuiting the same. In the position *g* (see Fig. 12), all but one starting resistances have been removed, while in position *h* all of the resistances have been short-circuited, this being the running position in full series connection. If it be desired, braking operations could be commenced when the main controller 200 has reached this position, and movement of the braking controller 300 to any of the positions *g* to *x* would result first 70 in the connection of the excitors Ea and Eb across the fields of the traction motors, and second in increasing the excitation of the shunt field of the excitors. 75

Transition from series to parallel.

80

Supposing that the braking controller has now been returned to the position *g*, then it will be possible to move the main controller from the position *h* to the position *e*, where 85 the pairs of traction motors will be connected in parallel to the trolley. Let us first consider the transition from the position *h* to the position *i*: As soon as the moving conductor on the controller drum 200, which 90 is associated with the control wire 152, has deenergized this wire, the coils 73a, 87a and 82a will be temporarily deenergized. The coil 125a, which has been previously deenergized through the opening of interlocks 95 73b and 87c, will remain deenergized because of the deenergization of wire 152. Because of the opening of the switch 73, the traction motors are now connected to the trolley only through the switches 71 and 72. The 100 energization of the control wire 153 will cause the coil 126a to be energized, as soon as the contactors 78 and 87 have dropped out closing the interlocks 73c and 87d, and the series parallel switch will be moved to 105 its parallel position. This switch is pneumatically operated, and although its operation only requires a few seconds of time, the sequence of steps during this interval is absolutely fixed, because of the fact that the 110 contacts on said switch are mechanically closed by means of rotating cams.

Switch transfer positions.

Referring to Figs. 4 and 5, it will be seen 115 that there are seven definite positions through which this switch passes, and that these have been designated by the reference characters T1 to T7. Referring, now, to Figs. 14 to 20, inclusive, it will be seen that 120 in the position T1, as shown in Fig. 14, the line contactor 73 is open and that the exciter Eb has been disconnected from the field windings of the traction motors B, this latter being caused by the deenergization of 125 the coil 87a, due to the opening of the circuit leading to the control wire 152. At the next step T2 three sections of the starting resistance S are inserted in series with the motors, while at step T3 the traction motors B 130

are short-circuited. The motors B are next disconnected from the other motors, first at one terminal (step T4), and then at the other terminal (step T5). At the next step 5 T6 one terminal of these motors is connected to ground, while at the next step T7 its other terminal is connected to the trolley by the closing of the contact 93. As soon as the series parallel switch has completed its 10 movement, the mechanically actuated interlocking contact 126b will be closed and will reenergize the operating coils 73a, 82a, and 87a of the contactors 73, 82 and 87 from the control wire 153. The exciter Eb is thereby 15 again connected across the field windings Bf of the motors B. The closing of contactors 73 and 87, through the opening of the interlocks 73c and 87d, causes the coil 126a to be deenergized and the air cylinder 20 to exhaust so as to be ready to transfer to series position without delay at the proper time.

Accelerating to parallel position.

25 The closing of the contactor 73 will reinsert the upper four starting resistances, while continued movement of the main controller 200 through the steps *j*, *o* will result in gradually cutting out these starting resistances, as will be evident from an inspection of Figs. 22 to 27, inclusive. Due to the mechanical interlocking of the two controllers, the braking controller 300 could not, during the movement from step *h* to step *o*, 30 be moved from its position *o*. As soon, however, as the main controller 200 has effected the full parallel connection of the motors, as represented in Fig. 27, the braking controller may be again rotated, which will 35 alter the excitation of the shunt field of the excitors in order to cause the traction motors to become generators and return energy 40 to the trolley.

45 **THE ELECTRICAL INTERLOCKING SWITCHES.**
As has been previously mentioned, the control circuits of the actuating coils for the various electromagnetic and electro-pneumatic switches are electrically interlocked one with another by means of interlocking switches mechanically connected to the main switches. Referring now, to Fig. 50 2, let us consider the functions of the various electric interlocks which have been provided: The circuit of the operating coils 121y and 122z of the reverser R is carried by the control wire 172 through interlocks 71b and 74b upon the line switches 71 and 74. It is, accordingly, impossible to throw 55 the reverser from one position to another while these line contactors are closed and any current is flowing through the reverser contacts. Interlocks 81c and 87b are also provided, to insure that the exciter armatures are disconnected from their respective 60 traction motor fields, in order that no current may be flowing therebetween when the reverser is operated to interchange the field terminals. The control wire 170 leads through interlock 89d upon the overload 65 relay to control wire 171, which branches through interlocks 102b and 102c to the coils 71a and 74a of the corresponding line switches. It will, therefore, be seen that the tripping of the overload relay, caused by 70 excessive currents through either of the coils 89a, will cause the opening of the line contactors 71 and 74. These interlocks 102b and 102c will always be closed during 75 motoring operations; *i. e.*, when the braking 80 controller 300 is in its off position, as shown, so long as control current is being supplied by the control generator C. 700a denotes a low voltage relay comprising contacts 700 which are maintained closed except when the 85 voltage of the generator C is below normal. During braking operations, however, one coil 102a of this motoring relay will only be energized through the control wire 181 when the interlock 127e is closed. This interlock is mechanically connected to the series parallel switch, and so arranged that it 90 will only be opened when such switch has been operated, in a manner to be later described, so as to cut out one pair of traction 95 motors. In the case where two locomotives equipped as herein described are running in multiple, and one such locomotive is operating with all four of its motors regenerating, while the other locomotive has two 100 of its motors cut out, this interlock 127e prevents the remaining two motors from 105 acting as motors to supply driving torque. This undesirable condition would necessarily obtain if the two motors were left in circuit, inasmuch as the vehicle with two motors cut out could not be operated for regenerative braking, due to the fact that the interlock just described would deenergize 110 the braking relay 101a, and hence could only be used for motoring. The coil 81a is energized through interlocks 101d and 80b. The interlock 101d will be closed as soon as the coil 101a of the braking relay is energized by movement of the braking controller 115 to any of its positions *q* to *x*. In other words, the exciter Ea can be connected across the fields Af of the traction motors whenever the braking controller is moved to any one of its operating positions, and regardless of the position of the reverser R (except the off position thereof) and the main controller 200 or the series parallel switch. Due to the interlock 80b, however, 120 it cannot be connected across said motor fields whenever the low resistance shunt is connected thereacross by closure of the switch 80 so that the possibility of thereby short-circuiting the exciter is avoided.

125 Let us now consider the interlocks in the 130

control wires 152 to 163: The coil 125a of the series parallel switch is energized from the wire 152 through the interlocks 73b and 87c. This insures that the line switch 73 shall have opened before the transition from parallel to series can be started, and that the contactor 87 shall have opened, thereby disconnecting the exciter Eb from the motor fields Bf when in regenerative braking it is desired to move the main controller from the parallel to the series position, thereby preventing the short-circuiting of the traction motors B with excitation on their fields from the exciter Eb. The function of this latter interlock should be effected by means of the auxiliary break 331, as will be later apparent. The reset coils 89r and 100r are also energized from the control wire 152 through interlocks 75b and 86b. Reference 20 to the table in Fig. 4 will show that only in the first position *a* of the main controller are both contactors 75 and 86 deenergized. Interlock 86e maintains the contactor 86 closed notwithstanding the opening of line 25 contactor 71 and consequently of interlock 71c due to the operation of the overload relay. If interlock 86e were not employed, the contactor 86 would open upon the opening of the interlock 71c and would cause 30 interlock 86b to close thereby energizing the coil 89r to reset the overload relay providing the controller is in position *h*. The overload continuing this cycle of operation would be repeated indefinitely. It, therefore, follows that the main controller must be returned to its position *a* in order to reset the overload and high voltage protective relays. The control wires 164 and 165 will be energized from the wire 152 when 35 the interlocks 125b and 89b are closed; that is to say, when the series parallel switch is in full series position, and when the overload relay is set. This insures that the line contactor 73 will not be closed in passing from parallel to series until the switch is thrown fully into the series position, and also that the first of the lower sections of the starting resistance S will not be short-circuited by the contactor 82. The interlock 89b provides means for opening the line contactor 73 when the overload relay trips out. It should be noted that the wire 152 is deenergized at the controller as soon as the full series position *h* has been passed, 45 and that the opening of contactor 73 starts the series parallel switch toward parallel position by closing the interlock 73c and energizing the coil 126a, provided that the control wire 153 is energized from the controller. It should also be noted that inasmuch as the coil 82a is connected directly in parallel with the coil 73a, that this contactor 82 will open at the beginning of transition. The function of the contactor 82 is 50 to make sure that all of the three lower sec-

tions of the starting resistance S (which is the correct amount for the transition) will be connected in circuit, even though one of the three contactors 83, 84, or 85 were closed at the time transition started. The coil 87a is energized from the control wire 164, provided that the interlocks 101e and 88b are closed. Interlock 101e is only closed when it is desired to begin braking, and interlock 88b insures that the exciter Eb cannot be connected across the traction motor fields Bf when a low resistance shunt is connected thereacross by the contactor 88. This arrangement of interlocks, it will be seen, is exactly the same as that provided for the contactor 81, and for the same purpose. 70

It should be noted that interlock 127b provides means for interconnecting the control wire 153 with the control wire 165. This interlock is only closed when the series parallel switch is manually operated, in a manner to be later described, so as to cut out one or the other pair of traction motors, as, for example, when this becomes necessary due to the break-down of one pair of motors. The closure of this interlock 127b, and the coincident opening of interlock 125b, allows line contactor 73 to be closed only when the main controller 200 is in the position for parallel connection of the motors. This provides, in the case where two locomotives are running in multiple, one of which is in perfect condition and the other of which has a pair of motors cut out, that current will not be supplied to the defective locomotive until the main controller 200 on the good locomotive has reached the parallel position. This keeps the load on the motors balanced. Interlock 126b, which only closes when the series parallel switch has completed its movement in the transition from series to parallel, allows the closure at this time of line contactor 73, thereby cutting into circuit the upper sections of starting resistance 100 S, and also contactor 82. Wire 153 leads through interlocks 73c and 87d to the control coil 126a of the series parallel switch, and insures that the said switch shall not be started toward its parallel position until 105 the line contactor 73 is opened, thereby leaving just the correct amount of resistance in circuit for the transition, and until the contactor 87 has opened so as to insure that the traction motors B shall not be short-circuited with excitation on their fields from the exciter Eb. Wire 154 leads through interlocks 89c and 127c to the coil 72a. The interlock 89c insures that the line contactor 72 shall open whenever the overload relay 110 trips out, and interlock 127c insures that all the starting resistances S shall be connected in series whenever one pair of motors is cut out. Wire 155 leads through parallel interlocks 71c and 86c and 127d 115

120 125 130

to coil 86a. The interlock 86e, which closes when 86 closes, renders it impossible for 86 to be tripped out upon the opening of line contactor 71, and hence interlock 71c, due to the operation of the overload relay and the opening of interlock 89d. Interlock 71c will only be closed when the coil 71a of the line contactor is energized through the reverser R. Obviously, the coil 71a will only be energized when the reverser has been thrown to the position indicated by the contacts 261 of the operating handle. It is, therefore, impossible to run two locomotives in multiple, on one of which the reverser had failed to operate. To be sure, failure of the reverser would prevent line contactors 71 and 74 from closing, but if contactor 86 were allowed to close under this condition, and the series parallel switch were in the parallel position, a circuit would then be established through contactor 86, contacts 93 and 97, to ground, thence to contacts 95 and 91, whereby the two sets of motors would be in parallel with each other. One of the pairs of traction motors would then act as a generator, and deliver current directly to the other pair of motors, which would act as motors, and slip the wheels. The interlock 127d prevents contactor 86 from closing when a pair of motors is cut out, and thereby insures that all the starting resistances S shall be in series with one another. Wire 159 passes through interlocks 86c or 83b to the coil 78a. When turning the main controller 200 on to the position *h*, the interlock 83b has no effect on the operation. The contactor 86 will close, however, before contactor 78 opens and this is desirable. Now, if the controller is moved to position *j* and then thrown back suddenly to position *h*, contactor 86 will remain closed and there is a possibility of contactor 73 also remaining closed so that contactor 78 might close while both contactors 73 and 86 remain closed were it not for these interlocks. This condition would give almost full parallel positions at full series speed, which would give a bad jolt to the locomotive. Therefore, the effect of these interlocks is virtually that of increasing the distance on the controller between the position *i*, where control wire 153 is deenergized, and the position *h*. When running the motors in parallel, the operation is not affected since contactor 83 is closed whenever contactor 78 is closed. Similar interlocks are provided in the control wire 162 for the coil 84a, and are utilized for a similar purpose. It is, therefore, believed to be unnecessary to recite the function in detail. Control wire 163 leads through interlock 81d to the coils 88a and 80a. This insures that whenever the regenerative braking contactor 81 is closed, it will be impossible to close the field shunting contactors, even if

the mechanical interlocking of the controllers, to be later described, should have enough back-lash to allow the wire 163 to be energized.

Let us now consider the interlocks in the control wires 181 and 182: The switch 700 remains closed so long as the control generator develops proper voltage. The function of the interlock 127e with respect to the coil of the motoring relay 102a has already been described; that is, that by its use the current is cut off from the locomotive whenever a pair of motors is cut out. This control wire 181 also leads through the coil 101a of the braking relay, and thence through an interlock 115 upon the motor-operated rheostat 118 (see Fig. 1) to the other side of the control generator. This interlock is closed only when the motor-operated rheostat is in the position where all of resistance 113 is cut into circuit. This insures that the rheostat shall always have returned to its full resistance position before it is possible to close the braking relay 101a and start regenerative braking. When the braking relay 101a has closed, it closes a holding circuit through the interlock 101c, so that this relay will stay closed even though the rheostat be moved to any desired position. Wire 182 leads through coil 103a of the transfer relay to the interlock 100b and the interlock 81b to the other side of the control generator. This transfer relay puts the motor-operated rheostat under the control of the contact-making ammeter 109, in a manner to be later described, and can only be closed when the high voltage relay 100 is in its set position and the regenerative braking contactor 81 is closed. The first of these interlocks insures that whenever the high voltage relay 100 is tripped, the motor-operated rheostat will be returned to its full resistance position, due to the dropping of the relay 103a, and the interlock 81b insures that the rheostat shall not be moved out of its full resistance position until the regenerating braking contactor 81 has been closed.

STRUCTURES OF CONTROLLERS.

The main controller.

115

From an inspection of Figs. 29 to 35, it will be seen that we have provided a main or motoring controller 200, having a suitable casing 201 which is provided with a removable front 202. On the top of this casing we have provided a supporting ledge 203 to which the casing of the braking controller may be attached. An operating handle 210 is provided for the main controller, and associated with this handle is a rack 211 and end stops 212 which limit the movement of the handle. In suitable positions upon the rack we have provided additional stops 213 and 214 to determine the position of the 130

handle for full series and full parallel connection of the traction motors. A finger latch 215 is pivoted upon the handle to engage the teeth of the rack 211, while in the 5 end of the handle we have provided a thumb latch 216 which cooperates with a pawl 216' (see Fig. 39) operatively engaging the stops 213 and 214. The movements of this handle are transmitted by means of a shaft 220 to an arm 221 (see Fig. 38), and thence through 10 a buffer spring 222 to a segmental gear 223 which meshes with a pinion 224, fastened to the upper end of the shaft 231 of the controller drum. Referring to Figs. 33 and 34, 15 it will be seen that suitable spiders 232 are keyed to this shaft, and that the controller drum is constructed somewhat after the fashion of a squirrel-cage 233, this being provided with vertical ribs 234, by means 20 of which the circular contact bars 235 are interconnected. Supporting lugs 236 are provided at either end of this squirrel-cage, and are secured by means of bolts to the spiders 232, suitable insulation being provided 25 between the squirrel-cage and the spiders and bolts, so that the controller drum consists of a series of movable contact members electrically interconnected, but insulated from all other parts of the structure. 30 By means of this squirrel-cage construction of the controller drum we are enabled to very considerably reduce the weight thereof over the well-known construction in which every contact member comprises a hub and a 35 circular plate having its rim suitably formed to act as a contact member. From Fig. 33, it will be seen that we have provided contact fingers 240 which are resiliently supported by means of springs 241 so as to make good 40 contact with the circular contact bars 235 of the squirrel-cage. The movement of these contact fingers is limited by means of finger stops 242, and terminals 243 are provided by means of which the control wires may be 45 conveniently attached thereto. Adjacent the contact fingers we have provided the usual blow-out coil 244, which is preferably pivotally mounted by means of supporting brackets 245 so that it may be turned out of 50 place in order to give access to the contact fingers. This blow-out coil is normally held in position by means of a latch 246 (see Fig. 55 31), and arc chutes 247 of insulation are preferably attached to the blow-out coil and are movable therewith.

In order to avoid danger of shock to the apparatus, we have provided a dash-pot 250, whose piston 251 is preferably attached to a lever 252 provided with an upstanding boss 253, this lever being conveniently rotatable about any suitable pivot point, as, for example, the shaft 231. A spring 254 is provided, which normally tends to withdraw the piston from the dash-pot. Attached to 60 the shaft 231, and rotatable therewith, is an 65

arm 255 which engages with the upstanding boss 253 to force the piston into the dash-pot upon the return of the controller drum to its off position. This structure, therefore, acts as a buffer, and prevents destruction of the 70 apparatus by rough usage.

The reverser.

Referring to Fig. 32, it will be seen that we have provided a reverser handle 260, 75 which is suitably connected by means of a link to rotating contacts 261, which co-operate with fixed contacts, preferably spring fingers, in the manner illustrated in Fig. 2. Adjacent the rotatable contacts 261, 80 and movable therewith, is a locking cam 263 which cooperates with a locking pawl 264 which is spring-pressed into notches in said cam and whose other end engages a notch 85 in the shaft 231 of the controller drum in such a way that the reverser may only be operated when the controller drum is in its off position, and, conversely, insures the reverser must be in an operating position before the main controller handle 210 may be 90 moved from its off position.

The braking controller.

Vertically superposed upon the main controller 200, we have provided a braking controller 300, which has its longitudinal axis substantially vertically above that of the main controller, and is so arranged that its operating handle is adjacent its lower end, and, consequently, adjacent that of the main controller, said handles being intermediate the top and bottom of the combined controllers. This braking controller is provided with a suitable casing 301 which is fastened in a convenient manner to a casing 302, which in turn is mounted upon the supporting ledge 203 of the main controller, and preferably bolted thereto. The braking controller is provided with an operating handle 303, whose latch 304 is arranged to co-operate with the teeth in the rack 305 mounted adjacent thereto. Operation of the braking controller handle causes rotation of the handle shaft 310, attached to which is an arm 311, and the movements 100 of this arm (see Figs. 36 and 38) are transmitted by means of a spring 312 to a segmental gear 313. This gear meshes with a pinion 314 upon the shaft 321 of the braking controller drum. This drum may be 105 constructed in any desired fashion, and comprises circular movable contact members 322 which engage contact finger 323 co-operating with which is the usual blow-out coil 324.

The auxiliary break.

In the casing 302, intermediate the braking controller proper and the main controller, we have provided an auxiliary break, by means of which, under certain condi- 110 115 120 125

tions, the circuit supplying control current to the electromagnetic switches and relays will be immediately broken upon backward rotation of the main controller handle. For the purpose of effecting this result, we have provided clutch shoes 330 (see Figs. 31 and 35) which are pivotally connected at one side and adjustably held by means of a thumb nut on the other side in frictional engagement with the shaft, or, rather, with an enlargement formed upon an extension of the shaft of the main controller. By an inspection of Figs. 31 and 32, it will be seen that this shaft extension is connected at 231' 10 by means of a rib and slot so as to be rotatable with the shaft of the main controller while vertically removable therefrom. Rigidly fastened to one of the clutch shoes 330 is a moving contact 331 adapted to bridge 20 contact fingers 332 in the manner shown in the control diagram in Fig. 2. Associated with these contacts is a blow-out coil 333, and preferably we would also provide arc chutes 334.

25 MECHANICAL INTERLOCKING OF THE CONTROLLERS.

Let us now consider the apparatus by means of which the handles of the two controllers are mechanically interlocked, as illustrated in Figs. 36, 37 and 38, and, incidentally, in Fig. 31. For ease of description, the actual construction will be pointed out in connection with a discussion of the 35 functions and operation of the apparatus involved.

First, we provide mechanism such that the main handle 210 must be in either the position *h* or *o* (see Fig. 2) so as to connect 40 the motors either in series or in parallel without the inclusion of any of the starting resistances *S*, before the braking handle 303 may be moved from its off position. This will prevent the locomotive from braking 45 through resistance. In considering the operation of the parts involved, it should be remembered that, when viewing the apparatus from above, rotation of the handles in a clockwise direction moves them from 50 their off positions to their operating positions, and that this movement produces a counter-clockwise rotation of the shafts 231 and 321 connected to the controller drums. In Figs. 31 to 38 all parts are shown in a 55 position corresponding to the off position of both handles. Associated with the braking handle shaft 310 is a disk 350, provided with a notch 357 in its periphery, and engaging this notch is the square end 356 of a bell 60 crank lever 351, which is spring-held in engagement therewith by means of a spring 352. The other arm 355 of this lever is provided with a roller engaging the surface of a cam 353, rotatable with the shaft 231 65 of the main controller and provided with

a recess 354 extending over a distance corresponding to a movement of the main controller shaft from the off position to the position *d*. After the main controller drum has been rotated beyond the position *d*, the 70 roller on the bell crank lever 351 will be lifted out of the recess 354 and will thereby remove its square end from the notch 357. It will be seen that by means of this device, rotation of the braking handle is prevented 75 until after the main handle has passed beyond position *d*. Supplementing the action of this device, we have provided a notched disk 360, having notches 361 and 362 corresponding to the series (*h*) position and 80 parallel (*o*) position of the main controller. This disk is rotatable with the main controller shaft and has associated therewith a bell crank lever 370 whose lower arm is provided with a pawl 371 adapted for engagement in the notches 361 and 362. The other arm 372 of the bell crank lever is provided with a roller adapted for engagement with the surface of a cam 380, rotatable with the shaft 321 of the braking controller. A 85 third arm 373 is also provided upon the bell crank lever 370, and the spring 352 may conveniently be attached thereto in such a manner that the roller on the arm 372 is held in engagement with the surface of the 90 cam 380. This cam 380 is provided with notches 381 and 382, corresponding to the off and *q* positions of the braking controller. A third notch 363 is provided in the disk 360, and corresponds in extent to the movement 95 of the main controller shaft 231 from the off to the *d* position thereof. Whenever the pawl 371 is in operative relation with one of the notches in the disk 360, the roller on the arm 372 of the bell crank lever may 100 be lifted out of the notches in the cam 380 and thus permit rotation of the shaft 321 of the braking controller. As far as these 105 elements are concerned, therefore, the braking controller might be operated when the main controller is being moved from the off to the *d* position. We have already seen, however, that co-operation of the bell crank lever 351 with the recess 354 and with the notch 357 in the disk 350 serves to prevent 110 movement of the braking controller during this interval. It, therefore, follows that the main controller shaft 231 must be rotated until the pawl 371 is opposite either the notch 361 or the notch 362 before the braking 115 controller may be rotated. 120

Second, we provide means to insure that the braking controller must be in either the off or the *q* position (see Fig. 2) before the main controller may be moved from the full 125 series (*h*) or full parallel (*o*) positions. It will be seen that this is a converse proposition from that just discussed, and that it is secured by the relation of the bell crank lever 370 with the cam 380 and the disk 360. 130

Third, we provide apparatus whereby the braking controller handle 303 may be moved from the *q* to the off position only by movement of the main controller handle to the off position. This result is assured by the provision of a stop 306 upon the rack 305 of the braking controller (see Figs. 30 and 38), and of a latch 390 in the handle 303 of said controller, which is adapted to pass freely over said stop during a clockwise or forward rotation of the braking controller handle, but cannot be returned to the off position because of the engagement of such parts. Upon the main handle 210 we have therefore, provided a lug 217, designed to engage and lift the latch 390 during the return movement of the main handle, and, further, to return the brake handle to the off position. It will be seen that the actual construction of the tooth 306 and the latch 390 which we prefer to use is not shown in the diagram in Fig. 38, but that the apparatus illustrated in Fig. 38 operates in exactly the same manner as our actual construction shown in Fig. 39.

Fourth, we provide means whereby it will be impossible, when the braking controller is in the position *q* to move the main controller from the position *o* to position *p*. This insures that under no circumstances will it be possible to connect the low resistance shunt for the motor fields across the terminals of the exciter armatures. To effect this result, we have provided a cam 400, mounted upon the shaft 231 of the braking controller, and preferably constructed as an integral part of the cam 380, and we have designed this cam with a notch 401 so arranged that when the braking controller is in the position *q*, it will be opposite the end of the roller arm 402 of a bell crank lever 403. This lever is provided in another plane with an arm 404 which is spring-pressed in a clockwise direction by means of a spring 405, and is provided with a square notch 406 adapted for engagement with the vertical surface of a lug 364 formed on the upper surface of the disk 360. With the parts in the positions shown, where both controllers are in the off position, this arm 404 is outside of the upstanding lug 364. If the main controller is rotated in a forward direction, however, the disk 360 will be rotated in a counter-clockwise direction, so that when the controller has reached the position *o*, the vertical face of the lug 364 will be opposite the notch 406 in the lower arm of the lever 403. If, then, the braking controller shall be in second position, the notch 401 will be opposite the end of the arm 402, and will allow the roller on the end of said arm to enter this notch. This will cause the square face of the notch 406 to be brought immediately in front of the vertical face of the lug 364, and will, con-

sequently, prevent further rotation of the main controller shaft 231 in a forward or counter-clockwise direction. As we have already seen, the main controller can only be moved from its position *h* or *o* when the braking controller is in either the off or the *q* position. It, therefore, follows that the main controller can never be moved to the *p* position so as to shunt the motor fields, except when the braking controller is in the off position. When the braking controller is in the off position, the exciter armatures will be disconnected from the motor fields, and all danger of short-circuiting the same will, therefore, be avoided.

Fifth, we also provide means whereby, with the braking controller in the *q* position, the turning of the main controller handle toward the off position from any position will operate an auxiliary break, which will interrupt the supply of control current and, consequently, open all the control circuits. We have already described a frictionally rotatable contact member 381 for effecting this result in so far as the opening of the circuit is concerned. It, therefore, only remains to describe the apparatus by means of which we prevent the operation of this circuit-opening device at any except the desired time. To this end we have provided an up-standing lug 335 upon one of the clutch shoes of the auxiliary break apparatus. Co-operating with this lug is the end of the arm 411 of the bell crank lever 410, whose other arm 412 is provided with a roller riding on the surface of the cam 400, and spring-held in this relation by means of a spring 413. Whenever the braking controller is in the off position, the roller of the arm 412 will drop into the notch 401 and bring the end of the arm 411 in front of the lug 335 on the auxiliary break. As a consequence, during motoring operations the rotation of the auxiliary break contact 381 in a clockwise direction is impossible. As soon, however, as the braking controller has been moved to the *q* or any succeeding position, the arm 411 will be moved away from the lug 335, so that return movement of the main controller handle 210 will cause a rotation of the frictionally engaging clutch shoes 330 in a clockwise direction, and thereby open the control circuit. As we have already seen, the main controller handle can only be returned to the off position when the braking controller handle is in the *q* position. However, the device just described is as effectually operated in this position as in any of the succeeding positions. One of the clutch shoes of the auxiliary break is also provided with a deep notch 336 and a shallow notch 337. In operative relation to these notches is a tooth upon the lower arm 421 of the bell crank lever 420, which is spring-pressed toward these notches by means of the spring 130

423, said bell crank lever being preferably pivoted upon the shaft of the lever 410, and readily rotatable thereabout. A cam 430 is mounted upon the shaft 231 of the main controller, and arranged in engagement with a roller upon the upper arm 422 of the bell crank lever 420. This cam is provided with a projecting portion 431, so arranged that when the main controller handle is in the off position it will engage said roller and lift the tooth upon the arm 421 out of engagement with the deep notch 336, while at all other times allowing the spring 423 to urge said tooth toward said notches. It will, therefore, be seen that if this braking controller is in the second position, and the main controller handle is rotated toward the off position, the auxiliary break 331 will be frictionally carried in a clockwise direction for a short distance until the tooth upon the arm 421 is engaged in the slot 336. Only a comparatively small rotation of this contact is necessary. When the main controller handle is returned to its off position, however, the arm 421 will be lifted out of engagement with the notch 336 and will be held out of said notch for a sufficient length of time, when the main controller handle is again rotated in a forward direction, to allow the auxiliary break to be rotated in a counter-clockwise direction to close its contacts. The arm 421 will then engage in the shallow slot 337 and prevent further rotation of the auxiliary break in this direction. It will be seen that we have, therefore, not only provided a construction such that the auxiliary break will be opened by a return movement of the main controller handle in any position if the braking controller is in the *q* position, but that we have also provided means whereby,

Sixth, this auxiliary break can only be closed by bringing the main controller handle to the off position and then again rotating it in the forward direction, and,

Seventh, the auxiliary break will not be opened if the braking controller handle is in the off position.

THE SERIES-PARALLEL SWITCH.

We will now proceed to describe the apparatus which we have termed a series parallel switch, by means of which the transfer from series to parallel is accomplished in a definite and predetermined sequence, as was described in connection with Fig. 5. This switch comprises an electro-pneumatically operated shaft, carrying cams by means of which the contacts are positively closed and opened, and also includes cut-out handles by means of which one or the other pair of motors may be disconnected if it is so desired. Referring to Figs. 40 to 51, inclusive, it will be seen that this switch comprises end frames 450 and 451, which are connected by

means of an angle-iron 452. Carried upon this frame-work are supporting end brackets 453, which are provided with hooks for the attachment of a sling when it is desired to move the switch about by means of a crane. Connecting the upper ends of these supporting brackets is a channel iron 454.

Contact construction.

Referring to Figs. 43 and 51, it will be seen that for each pair of contacts, we have provided a supporting bracket 460, suitably bolted to the channel iron 454, and a lower bracket 461 bolted to the angle-iron 452. Two tubes 462 of molded insulation are then bolted between the upper and lower supporting brackets. Porcelain spacers 463, separated by insulation washers 464, are mounted upon these tubes, and they are used to hold in proper position the contact tip supports. Of these, it will be seen that the upper contact tip support 470 is rigidly held to the insulating tubes by means of clamps 471, and carries a removable contact tip 472. A backwardly extending arm, formed integral with this support, provides means for the attachment of the terminal 473, by means of which the electrical connection with the upper contact tip is made. The lower contact 474 is carried upon an arm 475, which is pivotally mounted upon an operating lever 476. This lever in turn is pivoted to a support 477, which is suitably clamped to the insulating tubes in a similar manner as was the upper contact tip support. Between the operating lever 476 and the contact arm 475 we have provided springs 478 bearing against a spring seat 479 which is mounted to rock upon a pointed spring seat rocker 480. By means of this arrangement the contacts 472 and 474 are made to rub or wipe one another when being forced into contact, thereby insuring a clean contact surface. Provision is made at the back of the support 477 for the attachment of a terminal 481, by means of which electrical connections to the lower contact may be made. A flexible connection 482 is provided for electrically connecting this support 477, at a point adjacent the attachment of the terminal 481, with the contact arm 475, thereby avoiding the necessity of carrying any substantial current through the bearings of the operating lever 476. For the actuation of this operating lever 476, we have provided an operating rod 485, preferably constructed of wood, and have provided this rod with ferrule tips 486, by means of which it is pivoted to the contact lever 476 at its upper end, and to an operating lever 515 at its lower end.

Operating mechanism.

We have already stated that the switch was electro-pneumatically operated, and for

the sake of illustrating some means by means of which this result may be effected, we have shown the outline of an air engine 490. Pistons (not shown), which travel 5 horizontally within the cylinder of the engine, are suitably connected to the crank 491 mounted upon the shaft 495, said crank being provided with an extension 492, by means of which the movement of the shaft is 10 definitely limited. Valves 493, of which only the projecting spindles 494 can be seen, are electrically operated by the coils 125a and 126a indicated in Fig. 2, and control the admission of air to the opposite ends of the 15 engine 490 through pipes 496 which may be connected to a supply of compressed air or a similar suitable fluid. Bearings are provided for the operating shaft 495 in the end frames 450 and 451, and additional bearings 20 are provided by means of frames 455 and 456 depending from and bolted to the angle iron connecting member 452. Mounted upon the shaft 495, we have provided operating cams 500 to 509, inclusive, by means of 25 which its motion may be transmitted to the operating rods 485 and thence to the contacts of the various switches.

The contacts.

30 Referring to Fig. 43, it will be seen that near the margin of the drawing, and above each pair of contacts, we have applied the numerals 90 to 97, inclusive, to correspond to those employed in Fig. 5. For the sake of 35 simplicity, we have, in Fig. 5 and the various control diagrams, only shown those switches which are essential to a description of the operation of the device. In practice, however, it may be that high line voltages 40 make it desirable to employ two or more such switches in series, and it will be noted that in Fig. 43 we have shown twelve switches, whereas, in Fig. 5 there are only eight. We have, accordingly, applied the 45 numerals 93', 94', 94'', and 95' to indicate the switches corresponding to the switches 93, 94 and 95, which will be operated at the same times, and will be connected in series 50 with the said switches. The relative times of the opening and closing of the various contacts may be determined by reference to Fig. 5.

The operating cams.

55 The forms of the various operating cams have been shown in Figs. 47, 49 and 50. Cams 500, 502, 503, 507 and 508 are all of the form shown in Fig. 49, designated by the numeral 502, although they may occupy different angular positions upon the shaft. Cams 501, 504, 505 and 506 are all of the form shown in Fig. 50 and designated by the numeral 501. The cam 509 is of the special form illustrated in Fig. 47. Special devices, to be later described, are utilized

for the actuation of the contacts of switches 90 and 91. For the purpose of transmitting the motion of the various cams to corresponding operating rods, we have provided operating levers 515, one form of which is 70 illustrated in Figs. 47, 49 and 50, and it will be seen that said levers are pivotally mounted upon a support 516 which is bolted to the angle iron connecting member 452. At an intermediate point in said levers 515, we 75 have provided a roller 517, which bears against the cam surface, and by means of which the motion of the cam is transmitted to an operating rod during the closing operation. The springs 478 which have been 80 provided in connection with the lower contact tips 474 will normally be sufficient to cause the opening of the contacts. In order, however, that it may be unnecessary to rely upon such means, we have provided cross- 85 bars 518 at the lower end of the operating levers, whose rounded upper surfaces bear against the operating surfaces of the cams and cause the positive and rapid opening of the contacts. With reference to Fig. 49, it 90 will be seen that the delineation of the projection on the cam 502 is such as to bear against this cross-bar 518 and open the contacts. Similarly, in the form of cam illustrated in Fig. 50, a lower projection is provided for accomplishing a similar purpose. It will, therefore, be seen that the time of opening and closing the various contacts is 95 absolutely determined.

The cut-out handles.

100 We have previously mentioned that manually operated handles are provided for the purpose of cutting out a pair of motors. The actuation of either handle rotates the 105 main shaft of the switch to the position indicated by T6 in Fig. 5, in which it will be seen that the contacts 95 and 97 are closed. In addition, the operation of either handle will insure the closing of the contact 92, 110 while the operation of the inner handle 535 will close the contact 90 and open the contact 91 (see the dotted lines in Fig. 5). In other words, the operation of the inner handle 535 will cut out the motors A, and operation of the outer handle will cut out the 115 motors B, as hereinafter more fully explained. Referring, now, to Figs. 41, 42 and 43, it will be seen that the outer handle 520 is provided with a latch handle 521 connected by means of a link 522 to a latch 523. As will be seen from Fig. 42, the handle is freely rotatable upon the shaft 495, and is provided at its lower end with an interlock cam 524 and a jack shaft cam 525, said handle being retained in position upon the shaft by means of a collar 526. In connection with the handle 520, a locking arc 530 is mounted upon the end frame 450. This locking arc is provided with a deep notch 120

531 and a shallow notch 532 with which the latch 523 may engage. A stop 533 is also provided on the lower end of the locking arc to limit the motion of the cut-out handle. 5 In connection with this handle, we have also provided an interlock disk 538, which, as will be seen by reference to Fig. 42, is keyed to the shaft 495 and (see Fig. 41) is provided with a notch in which the latch 523 10 may engage. It will, therefore, be seen that before the cut-out handles can be operated, the series parallel switch must be returned to the series position, which is the position shown in the drawings, so that the latch 523 15 may engage in the notch of the disk 538. After having been so engaged, the cut-out handle 520 may be pulled down until the latch engages the stop 533. At this time the latch will be opposite the shallow notch 20 532 of the locking arc, and may be engaged therein for the purpose of securing the cut-out handle and the shaft in a fixed position. This result will be secured because of the fact that the notch 532 is of such a depth 25 that the latch will not be permitted to entirely disengage from the notch in the interlocking disk 538. By reference to Fig. 48 it will be seen that the inner handle 535 is similarly constructed, being provided with 30 a latch handle, link, and latch, as was the handle 520. A locking arc 534 is provided in connection with this handle, and its latch is adapted to be engaged in the notch of interlock disk 539, of exactly similar construction as the disk 538. Surrounding the shaft 495, and rotatable thereon, we have provided a sleeve 540 (see Figs. 42 to 47). Said sleeve may be provided with cranks 541 and 542, which are connected by means 40 of links 543 to operating levers 519. It will be seen that the operating levers 519 are of similar construction to the levers 515, but, that, because of their link connection to the operating crank, it is unnecessary to provide them with a lower extension. The 45 sleeve 540 is also provided with a cam 544, for a purpose to be later explained, and is connected to be rotatable with the inner handle by means of a rib and slot connection 50 545 (see Figs. 42 and 43), and is held in position upon the shaft by means of a collar 546. Adjacent the handle end of the series-parallel switch, and journalized in the end frame 450 and the middle frame 456, 55 we have provided a jack shaft 550. Keyed to this shaft are operating arms 551, 552 and 553, while spring arms 554 and 555 extend rearwardly from said shaft and provide means for the attachment of springs 556 by 60 which the shaft is normally held in the position shown in the drawings.

Operation of cut-out handles.

Let us suppose that it is desired to cut 65 out the motors B: It is, then, only necessary,

supposing that the switch is in the series position, to grasp the outer handle 520, and, by engaging the latch 523 in the notch of the interlock disk 538, to rotate the main shaft to a position corresponding to that indicated by T6 in Fig. 5. As a result, the contacts 91, 95, 95' and 97 will be closed, thereby connecting the motors A directly to the line, and disconnecting the motors B. At the same time, the jack shaft cam 525, by 70 engagement with the roller of the upstanding arm 551, will have caused a rotation of the jack shaft against the tension of the springs, and a raising of the arm 553 (see Figs. 43 and 47). The lower ferrule of the 75 operating rod of the switch 92 is made in a special form, and is provided with an extension 487, which carries a roller 488. The raising arm 553 will contact with this roller and cause the closing of the switch 92. The 80 cam 509 will, owing to the rotation of the shaft 95 by the cut-out handle, have been moved to such a position that it will not interfere with the operating lever 515.

If, on the contrary, it is desired to cut out 90 the motors A, it will only be necessary, supposing that the switch is in the series position, as shown in the drawings, to pull down the inner cut-out handle 535 until its latch engages the shallow notch on its locking arc 95 534. This will, as in the case of the outer handle, cause the rotation of the main shaft to a position to close the contacts 95, 95' and 97, and it will, through the rotation of the sleeve 540, bring the cam 544 into engagement with the arm 552 of the jack shaft, thereby lifting the arm 553 and closing the switch 92. At the same time, the rotation of this sleeve will effect a rotation of the cranks 541 and 542 so as to open contacts 91 100 and close the contacts 90, thereby putting the motors B in circuit and cutting out the 105 motors A.

The cut-out interlocks.

As has already been described in connection with the control circuits, certain interlocks are provided upon the series parallel switch, which are operated when one pair of motors is cut out, so as to thereby control 110 the operation of certain of the electromagnetically-operated contractors. These interlocking switches are mounted upon a supporting board 560 (see Figs. 41 and 43) which is rigidly attached to the supporting 115 bracket 453. Carried upon the supporting board 560 are fixed studs 561 which pass through said board and are adapted for connection with the desired control circuits. A contact-carrying rod 562 is pivotally mounted 120 by means of links 563 so as to be capable of an approximately up and down movement, and carried upon this rod are certain bridge contacts 564, adapted to coöperate with the fixed studs so as to interconnect op- 125 130

posite studs. These contacts 564 comprise plates, preferably provided with contact tips at their outer ends, which are mounted in blocks of insulation encircling the rod 562 and are spring-pressed in one direction by means of springs 565. Interlock operating levers 566 and 567 are pivotally mounted upon the end frame 450, and are provided with forked ends 568 for engaging a pin at the lower end of the contact-carrying rod 562, and are also provided with finger ends 569 for engagement with the interlock cams 524 and 537 rigidly attached to the cut-out handles. A suitable spring is provided for holding these finger ends in contact with the associated cam surface. It will, therefore, be seen from an inspection of Figs. 41 and 48 that the manipulation of either cut-out handle will draw down the contact-carrying rod 562 so as to close the upper interlock 127b and open the interlocks 127c, 127d and 127e. The connections of these interlocks are shown in Fig. 2.

26 The series and parallel interlocks.

In addition, interlocks are provided which are closed and opened in accordance with the movements of the main operating shaft of the series parallel switch. One of these, which we shall term the series interlock, is mounted upon a supporting bracket 570 attached to the middle frame 455, and carries an interlock switch 125b; the other, which may be termed the parallel interlock, is mounted upon a supporting frame 571 attached to the middle frame 456, and carries an interlock 126b. The structure of these interlocks may be clearly seen by reference to Fig. 49, wherein is shown the series interlock. Carried upon the support 570 are fixed contacts 572 and a moving contact mounted upon an operating rod 573 of similar construction to the cut-out interlock. This rod is actuated by means of an operating lever 574 normally spring-pressed in a direction to open the contacts, and moved in a direction to close the same by means of a cam 510, shown in dotted lines in Fig. 49. This cam is keyed to the main shaft, and a similar cam (not shown) is provided for the actuation of the parallel interlock. Insulation barriers 575 and 576 are preferably provided above and behind the support 570.

55 The arc chutes.

Referring, now, to Figs. 40 and 43, it will be seen that arc chutes, provided with sides 581 and 582, are arranged around each of the contacts 92 to 95', inclusive, these sides being mounted upon spacers 583 and 584, a cylindrical spacer 585 being also provided adjacent the front thereof. At those portions of the arc chutes which are most exposed to the flame of the arc, we have provided burning plates 586 which are prefer-

ably constructed of a similar material as the arc chutes; *i. e.*, of asbestos board or a similar insulating material. Suitable barriers 587 are mounted upon each side of the arc chutes, being spaced therefrom in any convenient manner, and being so designed that they extend back of the supporting brackets and insulating supports of each switch.

The modified contact construction.

It should be here noted that the switches 90, 91, 96 and 97, whose construction is shown in Fig. 51, differ slightly in construction from the switches 92 to 95', inclusive. The construction of the switches 92 to 95' 70 30 35 40 45 50 55 60 65 70 75 80 85 90 95 100 105 110 115 120 125 130 135 140 145 150 155 160 165 170 175 180 185 190 195 200 205 210 215 220 225 230 235 end frames are bearings 607, in which a cam shaft is journaled, and bearings 608, in which is journaled a rocker shaft. A ledge 609 is formed on the end frames for the 5 purpose of receiving a suitable cover (not shown).

The fixed contacts.

Mounted upon the cross plates 606 are 10 fixed contacts 610 which are electrically insulated from the cross plates by means of porcelain insulators 611. It will be observed that these insulators are of a generally oblong cross-section, for the purpose of 15 receiving two bolts through each insulator, so that all danger of the rotation of the contact attached to the insulator is avoided. If desirable, washers 612 may be provided at either end of the porcelain insulators, in 20 order to absorb shocks and prevent breakage thereof. Fastened, by means of the bolts above mentioned, to the porcelain insulators are contact brackets 613 which comprise a plate extending longitudinally of the 25 reverse and of such dimensions that it will coöperate with two of the moving contacts. Contact tips 614 are preferably provided on the contact plates, and each of the brackets is provided with a suitable terminal 615 by 30 means of which the incoming leads may be securely attached.

The moving contacts.

It will be seen that the fixed contacts just 35 described are secured one at each end of the cross plate 606, while at the intermediate point of said cross plate we have provided a supporting bracket 621 for the movable contacts 620. This bracket will preferably be 40 attached to the cross plate by means of porcelain insulators, washers, and bolts, in exactly a similar manner as were the brackets for the fixed contacts. Attached to this bracket, and preferably formed integral 45 therewith, is a terminal 622 for the attachment of an incoming lead, while the lower end of the bracket constitutes a bearing 623. Journaled in this bearing is a rocker arm 624 which comprises parallel sides each of 50 which is provided near its ends with two sets of bearings, and the two sides are rigidly connected by means of members 625 constituting spring seats, and also by means of stops 626. Journaled in one set of bearings, 55 near each end of the rocker, are rocking contacts 630, each of which is provided with a contact tip 631 adapted for engagement with the contact tips of the fixed contacts. These rocking contacts are also provided with 60 backward extensions 632, and with vertically extending stops 633 adapted to coöperate with the stops 626 upon the rocker arms. Springs are then interposed, with the aid of spring seats and rockers, between the 65 members 625 and extensions 632. These

springs exert a constant pressure, tending to maintain the contact tips in engagement when the contacts are closed, and at other times to rotate the rocking contacts against the fixed stops.

In order to provide some means of conducting the current from the terminals 622 and the bracket 621 to the rocking contacts without the necessity of carrying the same through the two bearings, we have provided 70 current-carrying springs 637, in the form of flat plates provided with forked ends, which engage the central pivot and end pivots, respectively. If desired, similar plates may be provided at either side of the 75 rocking contacts.

The operating mechanism.

Mounted in bearings 607 is a cam shaft 640, carrying cams 641, while a rocker shaft 85 642 is journaled in the bearings 608. Mounted on the rocker shaft are rocker arms 643 which are preferably arranged in pairs and held in position on said shaft by means of collars 644. These rocker arms are provided with rollers 645 for engagement with the operating surfaces of the cams, and are also provided with forked ends 646 in which are pivoted ferrule tips 647 of operating rods 648. The opposite ends of these rods 90 are provided with forked ferrules which engage pins in the lower set of bearings at each end of the rocker arms 624. It will be noted that the particular method of mounting the movable contacts insures that they 95 shall be positively brought into engagement with the fixed contacts with considerable force, and that the two contacts shall wipe or rub against one another in order to insure that the coöperating surfaces are kept clean. 100

The engine.

Oscillation of the cam shaft 640 is effected by means of an engine 650 (see Fig. 54), which is provided with a cylinder 651 with- 110 in which two rigidly connected pistons 652 are adapted to be reciprocated. These pistons are connected by means of a link 653 with a crank 654 mounted upon the cam shaft 640, and stop extensions 655 are provided upon the crank to limit the movement thereof. The ends of the cylinder are closed by means of castings 656 which constitute a combined cylinder head and valve casing. These castings 656 are provided with a passage 657 which normally communicates directly with an exhaust passage 658, and to which may be admitted a suitable fluid, as, for example, compressed air, through an inlet passage 659. An electrically controlled valve 660 comprises a stem 661, normally spring-pressed in an upward direction, and valve members adapted to simultaneously close the exhaust passage and open the inlet passage when depressed. A 120 130

suitable magnet, comprising a coil 122_z, surrounds the valve stem and is adapted to attract an armature 665 arranged upon said stem so as to thereby move the valve downward against the pressure of the spring. This movement will admit compressed air to one end of the cylinder so as to reciprocate the pistons and oscillate the cam shaft. A similar magnet embodying the coil 121_y 10 is arranged to control the valve at the opposite end of the cylinder.

The interlocks.

The energization of these coils has been 15 described in connection with Fig. 2, in which we have illustrated electrical interlocks comprising fixed and moving contacts. The mechanical structure of these interlocks is clearly illustrated in Figs. 52, 54, and 55, 20 from which it will be seen that we have mounted the moving contacts 122 and 123 upon a block 671 which is pivotally supported upon brackets 672 attached to the cylinder of the engine. An actuating link 25 673, which is pivoted to a crank 674 upon the cam shaft 640, is provided with a loose connection to the block 671. At the opposite end of this block we have provided a locking pawl 675 which is held by a spring 30 676 in engagement with notches upon the block 671, so that the block may only assume one of two positions, such as are indicated by the letters *y* and *z* in Fig. 2. Arranged in operative relation to the moving 35 contacts are fixed contacts 677 which comprise a finger block 678 on which are mounted spring fingers 679, said fingers being provided with terminals 680 and with rigid plates 681, which constitute stops and 40 protecting means therefor.

From an inspection of Figs. 52 and 56 it will be seen that the cams 641 are so mounted upon the cam shaft that the adjacent moving contacts 620 are oscillated in opposite 45 directions, so as to make contact with those fixed contacts 610 which are arranged at opposite ends of a cross plate 606. It will be seen from Fig. 56 that the motor field windings are grouped in pairs, and that the 50 free terminals of two such windings are connected to the terminals of two adjacent moving contacts. It, therefore, follows that oscillation of the cam shaft, due to the energization of one or the other of the coils 121_y 55 and 122_z from the reverser handle 260, would cause an oscillation in opposite directions of two adjacent moving contacts 620 so as to reverse the relative connection with the corresponding motor field windings.

Regenerative braking operation.

Having described the construction and operation of the various parts involved, we will now describe the operation of our

system of control as a whole, and the relation and coöperation of the parts. Let us suppose that it is desired to start the locomotive from standstill, and, after having accelerated the same, to employ regenerative braking to hold the speed of the locomotive practically constant at any desired value, and then, because of change in grade or other external condition, that it is desired to materially increase the speed thereof. The reverser handle 260 will first be thrown into a position corresponding to motoring in a forward direction, and as soon as the main controller handle 210 has been thrown to the first position, so as to close the contacts 331 of the auxiliary break, one coil, for example coil 121_y, of the reverser operating mechanism will be energized, and will cause the reverser contacts to be thrown to the desired position. At the same time, the placing of the main controller in the first position *a* will have energized the reset coils 89_r and 100_r of the overload relay and the high voltage relay, respectively, and will have also energized the coil 125_a to cause the series parallel switch to assume its series position. The locomotive may now be accelerated in the usual manner by movement of the main controller handle to the position *b*, where, as will be seen from an inspection of Fig. 18, the motors are connected in series without the inclusion of any of the starting resistances *S*.

Motors in series.

If it is now desired to brake the locomotive at a speed, for example, sixteen miles per hour, corresponding to the series position, then the braking controller handle 303 may be moved from its off position to its equalizing position *q*. It should be here noted that although but one coil of the motoring relay 102_a is energized directly when the braking controller is in its off or motoring position, yet when this controller is turned to its equalizing or any subsequent position, then the other coil only of the motoring relay 102_a is energized through the contacts of the interlock 127_e. As a result, where two locomotives are running in parallel, and it is necessary to cut out one pair of motors on one of these locomotives, then, owing to the opening of the interlock 127_e, the motoring relay cannot be energized in any of the braking positions, and, consequently, the line contactors 71 and 74 cannot be closed. It is, therefore, impossible to brake with the locomotive upon which two motors are cut out.

If, however, the locomotive is in good condition, then we may proceed with regenerative braking by movement of the braking controller to its equalizing or *q* position and to the subsequent positions. At the equaliz-

ing position, the relay 101a will be energized, and will set in operation the motor 110 of the automatic rheostat 118, and will also permit the closure of the contactors 81 and 87, to connect the excitors E_a and E_b across the motor fields. Because of the interlock 115 on the motor-operated rheostat, the relay 101a can only be energized if this rheostat is in such a position as to include the whole of the resistance 113 in the circuit of the shunt field winding 130 of the exciter E . Once this relay is energized, however, the interlock 101c will close the holding circuit and keep the same energized, regardless of the position of the motor-operated rheostat. It will be seen that, since the relay 103a was deenergized when the braking controller was turned to its off or motoring position, this relay thereby, through its lower contacts, kept the clutch coil 111 energized so as to return the motor-operated rheostat to its full resistance position at the close of the previous operation. When this position was reached, the limit switch 116 was opened by the arm 114, and the circuit of the clutch coil 111 and the motor broken. A similar limit switch 117 is provided to open the circuit of the clutch coil 112 when all the resistance has been short-circuited. Further, at this equalizing position g , the voltage of the excitors will be substantially or approximately equal to the drop across the motor field windings A_f and B_f , due to the excitation furnished by the series winding 131, which is connected to carry the full current passing through the traction motors, and the shunt winding 130, the excitation of which in this position is at a constant minimum value. Accordingly, this excitation will vary as the current through the motor fields varies, and the exciter voltages will be automatically adjusted to equal the drop across the motor fields. At this time, when the whole of the resistance 113 is included in the shunt field circuit, the excitation produced by this shunt field winding 130 is very small, and may be negligible. Let us suppose that the braking controller is now moved to its position r , then the reversing relay 104a will be closed, and current will be supplied from the control generator to the shunt coil 106 of the contact-making ammeter 109. In addition, the transfer relay 103a will be energized and will give over the control of the rheostat 118 to the ammeter 109. With these connections, the coil 106 will be given its maximum energization in a direction to aid the coil 107. The contact arm 108 is held in mid-position by a predetermined pull on its core, a spring being provided to partially balance the weight of the core. If, then, the coils 106 and 107 are aiding, and coil 106 is energized to its maximum amount, only a very small current in the coil 107 will be needed in order to secure this pull. The result is, that if the current flowing through the exciter armature E_a exceeds this necessary amount, the rheostat 118 will be operated in such a direction as to decrease the current through the shunt field winding 130, and if the current in the coil 107 falls below this amount, the shunt excitation of the exciter E will be increased, so that the current flowing through the exciter armatures will be maintained constant at some predetermined value. Supposing that it has been desired to increase the degree of braking, the handle 303 of the braking controller will be rotated in a direction to bring the same to the positions s and t , thereby including a resistance in series with the coil 106. This will result in holding the current through the exciter armatures constant at a larger value, because of the increased current that will be required in the coil 107 in order to maintain the arm 108 of the contact-making ammeter in its mid-position. In the position u , the circuit of the coil 106 will be entirely broken, and, consequently, the coil 107 must furnish the entire pull. At the next step v , the relay 105a will be energized to close its contacts 105, and thereby supply a small current in the reverse direction through the coil 106. This coil 106 is now opposing the coil 107, so that a still larger current will be required in order to maintain a balanced position of the contact-making ammeter arm. Subsequent positions of the braking controller will simply reduce the resistance in series with the coil 106, and, therefore, increase the current through the same, and cause an increase in the braking effect produced.

Protective devices

105

If at any time during the braking operations the trolley T should come off, so as to interrupt the connection between the supply of current and the locomotive, then it will be seen that the current flowing through the series field winding 131 of the exciter will very quickly be reduced to zero, and will thereby remove its bucking effect and allow the excitation produced by the shunt field winding 130 to exert its full effect. Such a sudden increase in the excitation delivered to the traction motors while they are acting as generators will usually produce an excessive voltage on the locomotive, and this in turn will produce an excessive voltage upon the driving motor M of the motor-generator set, and will, consequently, energize the coil 100a of the high voltage relay sufficiently to trip the same. Since, as will be seen from an inspection of the drawing, the short-circuiting effect of the arm 114 on the resistance 113 is dependent upon the maintenance of the circuit through the contacts 100, then

the opening of these contacts will immediately cause the insertion of the whole of the resistance 113 in the shunt field circuit of the exciter, and will thereby remove the excessive excitation, which might otherwise become very destructive. Further, if the current flowing through the traction motors becomes excessive at any time, either during motoring or braking operations, the trip coil 89a of the overload relay will become energized sufficiently to open its contacts 89b, 89c, and 89d, and to thereby deenergize the line contactors 71, 72, 73, and 74. As has been previously pointed out, the provision of the interlocks 75b and 86b in the circuit of the reset coils 89r and 100r makes it necessary to return the motoring controller to its first position before these coils can be energized. Because of the interlocking of the two controllers, if either of these relays becomes tripped during braking operations it will also become necessary to return the braking controller to the *g* position, whereupon the main controller may be returned to its off position, and this will in turn return the braking controller to its off position.

Series parallel transfer.

Let us suppose, however, that after braking with the motors arranged in full series relation, it is desired to increase the speed of the locomotive by braking with the motors in parallel relation. It then becomes necessary to return the braking controller to its equalizing or *g* position in order that the motors may not try to regenerate through the starting resistances *S*, and, further, in order that one exciter armature may not be short-circuited during the transition from series to parallel. We have already seen that the mechanical interlocking of the two controller handles is such that this sequence of operation is insured. Supposing that the braking controller handle has now been returned to its equalizing position *g*, then the rotation of the main controller handle toward the position *o* may be started. As soon as the position *i* is reached, the coil 126a of the series parallel switch will be energized, and will cause the series parallel switch to throw over, thereby effecting exactly in sequence the connections illustrated in Figs. 14 to 20, inclusive. It will be seen from an inspection of these figures, that, although the exciter *Eb* has been disconnected for reasons previously stated, the exciter *Ea* has remained connected across the motor field windings *Af*. However, inasmuch as the coil 103a has become deenergized as soon as the braking controller was returned to the equalizing position *g*, the transfer relay 103a has thereby caused the return of the motor-operated rheostat 118 to its full re-

sistance position, thereby decreasing the excitation produced by the shunt field winding 130 to a negligible amount. Upon the return of the braking controller handle from the position at which regenerative braking was being carried on to its equalizing or *g* position, the current regenerated by the traction motors will have quickly, but perfectly gradually, been reduced to a very small amount. This current may be reduced to such an amount that regeneration will actually cease, and that current will be supplied to the traction motors. As a consequence, it will be necessary, in order to prevent the locomotive from running away, to apply the air brakes. Owing to the fact that the shunt field excitation of the exciters has been decreased to a negligible amount, and owing to the fact that the excitation supplied by the series field winding 131 is such that the voltage across the exciters is maintained substantially equal to the drop across the field of the traction motors, then it will be seen that no harm results from the fact that the exciter *Ea* remains connected across the field windings *Af*. All of these steps of transition will be carried out automatically and mechanically by means of the series parallel switch, without thought on the part of the operator, and, in fact, will proceed so quickly that it will take place during the time that the main controller is being moved from the position *i* to the position *o*. The movement of the main controller handle may now be continued so as to effect the connections shown in Figs. 21 to 27, inclusive; the last of these, corresponding to the position *o* of the main controller, provides for the connection of the traction motors in pairs in parallel directly to the line, without the inclusion of any of the starting resistances *S*. It will be seen from an inspection of Figs. 21 to 27, inclusive, that we have shown both exciter armatures connected across the motor field windings throughout all of the steps *i* to *o*. Inasmuch, however, as the braking controller must be in its equalizing or *g* position during this movement of the main controller, and since the transfer relay 103a is, therefore, deenergized, the excitation produced by the shunt field winding 130 will be negligible, and the exciter voltages will practically equal the drop across the motor fields, so that they will have no effect upon the operation of the traction motors.

Motors in parallel.

As soon as the main controller has been moved to the full parallel position, the mechanical interlocking between the handles of the two controllers will allow movement of the braking controller so as to increase

the excitation of the excitors and thereby cause the traction motors to regenerate at speeds in the neighborhood of the speed, say thirty-two miles an hour, corresponding to 5 the full parallel connection of the traction motors.

Return to motoring.

Let us suppose, now, that after braking 10 with the traction motors connected in parallel, it is desired to utilize the motors to supply tractive energy to the train, then it is necessary to first return the braking controller to its equalizing or *q* position, 15 where the current regenerated is reduced to practically zero. The braking controller handle may not, however, be moved back to its motoring or off position, because if such a procedure were allowable the movement 20 of the braking controller handle might be so fast that the motor-operated rheostat would be unable to follow it up and reduce the braking torque produced as quickly as is desired. The consequence would be, that it 25 might be possible to change the operation from a condition where the motors were regenerating a considerable current, and, therefore, producing considerable braking torque, to a condition where the motors were 30 connected in parallel and arranged to receive energy from the line, and could, therefore, produce a very considerable motoring torque. Such a sudden change of conditions would produce a very bad shock to the 35 locomotive and the attached train, and might be sufficient to cause considerable damage. We have, accordingly, in the manner previously described, so interlocked the two controller handles, that in order to move 40 the braking controller handle from its equalizing or *q* position to a motoring or off position, the main controller handle must be returned to its off position. When it has 45 reached its position *d*, it will automatically cause a return of the braking controller to its off position.

As will be understood from the description already given, the return movement of the main controller handle from its full 50 parallel (*o*) position to any other position while the braking controller handle is in its equalizing position will immediately open the contacts 331 of the auxiliary break. This will immediately deenergize all of the 55 electromagnetically-operated switches and thereby disconnect the traction motors from the trolley. We have thereby prevented the operation of changing over from a condition of braking, due to the motors connected in 60 parallel, to a condition where the motors are connected in series. If such an operation were possible, it will be seen that the braking torque might be so suddenly in-

creased as to produce a bad shock, and, furthermore, might allow of braking with 65 the starting resistances *S* connected in series. Accordingly, if after braking with the motors connected in parallel it is desired to brake with the motors connected in series, it is necessary for the operator to 70 first return the braking handle to the equalizing position, and then to return the main handle to its off position, which will, at the same time, return the braking controller handle to its off position, and to then return 75 the main controller handle to the series (*h*) position, and thereupon proceed with the braking operation as desired.

Although we have herein described one preferred embodiment of our invention, it 80 will be understood that we do not desire to be limited thereto, but seek to cover in the appended claims all modifications which come within the scope and spirit of our invention.

What we claim as new and desire to secure by Letters Patent of the United States, is:—

1. In combination, a plurality of electric motors, a controller for connecting said 90 motors in series and in parallel, a source of current adapted to be connected to the field winding of each of said motors, a controller arranged to control the connection between said source of current and said field winding, and means for determining the relative 95 operation of said controllers.

2. In combination, a plurality of series electric motors, a power supply circuit, resistances, a controller connected and arranged to control the connections between said power supply circuit, said resistances, and said motors, and to connect said motors directly in series and in parallel with said source of supply, means for causing said 100 motors to act as generators, a controller for controlling said latter means, and means mechanically connecting said controllers arranged to prevent the operation of said 105 latter controller when said first controller is in such a position that the resistances are connected in circuit.

3. The combination of an electric motor with two controllers for controlling said motor, said controllers being vertically superposed with their longitudinal axes substantially end to end, each controller being provided with an operating handle, said handles being arranged adjacent one another intermediate the top and bottom of 120 said controllers.

4. The combination of an electric motor with two controllers for controlling said motor, said controllers being vertically superposed with their longitudinal axes substantially end to end, each controller being 125

- provided with an operating handle, said handles being arranged adjacent one another intermediate the top and bottom of said controllers, and means connecting said handles to determine the relative operation of said controllers.
5. The combination of a plurality of electric motors, a series parallel controller for said motors, a braking controller for causing said motors to operate as braking generators, and means preventing the operation of said braking controller unless the motor circuit has first been closed by the operation of the series parallel controller.
10. In combination a plurality of series electric motors, a power supply circuit, a series parallel controller for said motors, an auxiliary source of supply, a braking controller for connecting said auxiliary source of supply to the field windings of said motors to cause said motors to act as generators, means preventing the movement of said braking controller to energize said field windings from said auxiliary source except when said series parallel controller is in its full series or its full multiple position, and means operated by movement of the braking controller for locking said series parallel controller in the position which it then occupies.
15. 6. The combination of an electric motor, a controller for controlling the operation of said motor while the same is absorbing electrical energy, said controller having a movable element rotatable about a vertical axis and provided with an operating handle adjacent its upper end, a braking controller for controlling the operation of said motor so that the same shall deliver electrical energy, said controller having a movable element rotatable about a vertical axis and provided with an operating handle adjacent its lower end, said braking controller being detachably secured to the upper end of said first-named controller.
20. 7. The combination of an electric motor, a controller for controlling the operation of said motor while the same is absorbing electrical energy, said controller having a movable element rotatable about a vertical axis and provided with an operating handle adjacent its upper end, a braking controller for controlling the operation of said motor so that the same shall deliver electrical energy, said controller having a movable element rotatable about a vertical axis and provided with an operating handle adjacent its lower end, said braking controller being detachably secured to the upper end of said first-named controller, and means associated with said controllers for determining their relative operation.
25. 8. In combination a plurality of series electric motors, a power supply circuit, a series parallel controller for said motors, an auxiliary source of current supply, a braking controller for connecting said auxiliary source to the field windings of said motors to cause the motors to act as generators, and means whereby said braking controller may be operated only when the series parallel controller occupies certain predetermined positions.
30. 9. In combination a plurality of series electric motors, a power supply circuit, a series parallel controller for said motors, an auxiliary source of current supply, a braking controller for connecting said auxiliary source to the field windings of said motors to cause the motors to act as generators,
35. means for locking the braking controller against movement and means operated by the series parallel controller for disengaging said locking means when the series parallel controller occupies its full series or its full multiple position.
40. 10. In combination a plurality of series electric motors, a power supply circuit, a series parallel controller for said motors, an auxiliary source of supply, a braking controller for connecting said auxiliary source of supply to the field windings of said motors to cause said motors to act as generators, means preventing the movement of said braking controller to energize said field windings from said auxiliary source except when said series parallel controller is in its full series or its full multiple position, and means operated by movement of the braking controller for locking said series parallel controller in the position which it then occupies.
45. 11. In combination, a plurality of series electric motors, a power supply circuit, a series parallel controller for said motors, an auxiliary source of supply, a braking controller in one position of which said auxiliary source of supply is caused to have a minimum excitation and is connected to the field windings of said motors to cause said motors to act as generators and in another position of which said auxiliary source of supply is disconnected from the field windings of said motors, and means preventing the movement of the series parallel controller from the full series position or the full parallel position unless the braking controller is in one or the other of said positions.
50. 12. In combination a plurality of series electric motors, a power supply circuit, a series parallel controller for said motors, an auxiliary source of supply, a braking controller for connecting the field windings of said motors to said auxiliary source, means preventing the operation of said braking controller except when the series parallel controller is in its full series or its full multiple position and means for preventing the movement of the series parallel controller after the braking controller has been operated except when the braking controller occupies a position corresponding to a minimum excitation of the fields of said motors.
55. 13. In combination, a plurality of series electric motors, a power supply circuit, a series parallel controller for said motors, an auxiliary source of supply, a braking controller for connecting said auxiliary source to the field windings of said motors, and means for preventing the closure of the motor circuit by the operation of the series parallel controller unless the braking controller is in its off position.
60. 14. In combination, a plurality of series

- electric motors, a power supply circuit, a series parallel controller for said motors, an auxiliary source of supply, a braking controller for connecting said auxiliary source to the field windings of said motors, means controlled by the series parallel controller for preventing the disconnection of the auxiliary source from the fields of the motors, and means for preventing the closure of the motor circuit by the operation of the series parallel controller unless the braking controller is in its off position. 10
15. In combination, a plurality of series electric motors, a power supply circuit, a series parallel controller for said motors, an auxiliary source of supply, a braking controller for connecting the auxiliary source to the field windings of said motors, means for preventing the closure of the motor circuit by the operation of the series parallel controller unless the braking controller is in its off position, and means whereby the movement of the braking controller into an operating position completes a maintaining circuit for the switches controlling said motor circuit. 20
25. In combination, a plurality of series electric motors, a power supply circuit, a series parallel controller for said motors, an auxiliary source of supply, a braking controller for connecting the auxiliary source to the field windings of said motors, means for preventing the closure of the motor circuit by the operation of the series parallel controller unless the braking controller is in its off position, means whereby the movement of the braking controller into an operating position completes a maintaining circuit for the switches controlling said motor circuit, and means controlled by the series parallel controller for preventing the disconnection of the auxiliary source from the fields of the motors. 30
35. In combination, a plurality of series electric motors, a power supply circuit, a series parallel controller for said motors, an auxiliary source of supply, a braking controller for connecting said auxiliary source to the field windings of said motors, and means controlled by the series parallel controller for preventing the disconnection of the auxiliary source from the fields of the motors. 40
45. In combination, a plurality of series electric motors, a power supply circuit, a series parallel controller for said motors, an auxiliary source of supply, a braking controller for connecting the field windings of said motors to said auxiliary source, and electrical connections between said series parallel controller and contacts on the braking controller which are closed only in the off position of said braking controller for controlling the closure of the motor circuit. 50
55. The combination of a motor provided with a series field winding, a shunt for said winding, a source of current adapted to be connected to said field winding, means for connecting said shunt to said winding, means for connecting said source to said winding, and means for preventing the simultaneous operation of said connecting means. 65
60. The combination of a plurality of motors provided with series field windings, resistance shunts adapted to be connected across said windings, a series parallel controller for said motors arranged in one position to connect said shunts to said field windings, a braking controller for causing said motors to operate as braking generators, and means actuated by movement of the braking controller to an operative position for preventing movement of said series parallel controller to the position for connecting said shunts. 70
75. The combination of a power supply circuit, an electric motor, a starting resistance therefor, an auxiliary source of current, with a controller for controlling the connections of said motor and resistance to said power supply circuit, means for connecting said auxiliary source of current to the field winding of said motor, and means rendered operative by the closure of said latter connecting means whereby a reverse movement of said controller will immediately break a connection in the power circuit of said motor. 80
85. The combination of a power supply circuit, a plurality of electric motors, auxiliary sources of current, with a controller for interconnecting said motors to said power supply circuit, means for connecting said auxiliary sources to the field windings of said motors, and means rendered operative by the closure of said latter connecting means whereby a reverse movement of said controller will immediately break the power circuit through each of said motors. 90
95. In combination a plurality of series electric motors, a power supply circuit, a series parallel controller for said motors, an auxiliary source of supply, a braking controller for connecting said auxiliary source to the field windings of said motors, means for preventing the braking controller from being moved into an operating position except when the series parallel controller occupies its full series or its full parallel position, means for preventing the movement of the series parallel controller from either of these positions except when the braking controller is in a predetermined position, and means whereby a movement of the series parallel controller from its full parallel position toward the off position causes the motor circuit to be opened. 100
105. The combination of a power supply circuit, a plurality of electric motors, auxiliary sources of current, with a controller for interconnecting said motors to said power supply circuit, means for connecting said auxiliary sources to the field windings of said motors, and means rendered operative by the closure of said latter connecting means whereby a reverse movement of said controller will immediately break the power circuit through each of said motors. 110
115. In combination a plurality of series electric motors, a power supply circuit, a series parallel controller for said motors, an auxiliary source of supply, a braking controller for connecting said auxiliary source to the field windings of said motors, means for preventing the braking controller from being moved into an operating position except when the series parallel controller occupies its full series or its full parallel position, means for preventing the movement of the series parallel controller from either of these positions except when the braking controller is in a predetermined position, and means whereby a movement of the series parallel controller from its full parallel position toward the off position causes the motor circuit to be opened. 120
125. In combination a plurality of series electric motors, a power supply circuit, a series parallel controller for said motors, an auxiliary source of supply, a braking controller for connecting said auxiliary source to the field windings of said motors, means for preventing the braking controller from being moved into an operating position except when the series parallel controller occupies its full series or its full parallel position, means for preventing the movement of the series parallel controller from either of these positions except when the braking controller is in a predetermined position, and means whereby a movement of the series parallel controller from its full parallel position toward the off position causes the motor circuit to be opened. 125

24. In combination a plurality of series electric motors, a power supply circuit, a series parallel controller for said motors, an auxiliary source of supply, a braking controller for connecting said auxiliary source to the field windings of said motors, and means whereby a reverse movement of the series parallel controller will immediately open the motor circuit provided the braking controller is in a position to connect said auxiliary source to the field of the motor.

25. In combination a plurality of series electric motors, a power supply circuit, a series parallel controller for said motors, an auxiliary source of supply, a braking controller for connecting said auxiliary source to the field windings of said motors, means preventing the operation of said braking controller except when the series parallel controller is in its full series or its full multiple position and an auxiliary switch arranged to be operated by a reverse movement of the series parallel controller to open the motor circuit.

26. In combination a plurality of series electric motors, a power supply circuit, a series parallel controller for said motors, an auxiliary source of supply, a braking controller for connecting said auxiliary source to the field windings of said motors, means preventing the operation of said braking controller except when the series parallel controller is in its full series or its full multiple position, means for preventing the braking controller from being returned to its off position after it has been moved into an operating position and an auxiliary switch operated by a reverse movement of the series parallel controller to open the motor circuit.

27. In combination a plurality of series electric motors, a power supply circuit, a series parallel controller for said motors, an auxiliary source of supply, a braking controller for connecting said auxiliary source to the field windings of said motors, an auxiliary switch for controlling the main motor circuit, means for opening said switch by a reverse movement of the series parallel controller, and means for preventing the movement of the auxiliary switch to open the motor circuit when the braking controller is in its off position.

28. In combination a plurality of series electric motors, a power supply circuit, a series parallel controller for said motors, an auxiliary source of supply, a braking controller for connecting said auxiliary source to the field windings of said motors, an auxiliary switch for controlling the main motor circuit, means for opening said switch by a reverse movement of the series parallel controller, means for preventing the movement

of the auxiliary switch to open the motor circuit when the braking controller is in its off position, and means for closing said auxiliary switch only by a movement of the series parallel controller from its off position.

29. In combination, a plurality of series electric motors, a power supply circuit, a series parallel controller for said motors, an auxiliary source of supply, a braking controller for connecting said auxiliary source to the field windings of said motors, an auxiliary switch for controlling the main motor circuit, means for opening said switch by a reverse movement of the series parallel controller, and means for preventing the movement of the auxiliary switch to open the motor circuit when the braking controller is in its off position.

30. In combination a plurality of series motors, a power supply circuit, a series parallel controller for said motors, an auxiliary source of supply, a braking controller for connecting said auxiliary source to the fields of said motors, means for preventing the operation of said braking controller except when the series parallel controller occupies its full series or its full multiple position and means controlled by the series parallel controller for preventing the disconnection of the auxiliary source from the fields of the motors except by movement of the series parallel controller to its off position.

31. In combination a plurality of series electric motors, a power supply circuit, a series parallel controller for said motors, an auxiliary source of supply, a braking controller for connecting said auxiliary source to the field windings of said motors, means for preventing the movement of said braking controller into an operative position except when the series parallel controller is in its full series or its full multiple position, and means for preventing the braking controller from being returned to its off position except by movement of the series parallel controller to its off position.

32. In combination a plurality of series electric motors, a power supply circuit, a series parallel controller for said motors, an auxiliary source of supply, a braking controller for connecting said auxiliary source to the field windings of said motors, means for preventing the movement of said braking controller into an operative position except when the series parallel controller is in its full series or its full multiple position, and means for returning the braking controller to its off position by movement of the series parallel controller to its off position.

33. In combination, a power supply circuit, a pair of series motors, an auxiliary source of current connected to the field winding of each of said motors, means for con-

necting said motors in series and in parallel to said power circuit, means for maintaining the power circuit closed through one of said motors and disconnecting the auxiliary source of current from the other of said motors and reducing the potential of the source connected to first motor during the transfer from series to parallel.

34. The combination of a power supply circuit, and a plurality of series motors with means for connecting said motors in series and in parallel to said circuit, and for keeping the current flow to or from the power circuit uninterrupted during said change, an auxiliary source of current connected to the field winding of each of said motors, means for disconnecting the auxiliary source from one of said motors during the transfer from series to parallel, and means for adjusting the voltage of the source connected to the field winding of that motor which remains

connected to the power circuit so that it equals the potential drop across the same.

35. In combination, a source of supply, a pair of series motors, means for connecting said motors in series and in parallel to said source of supply by short-circuiting one of said motors while keeping the flow of current through the other motor uninterrupted, an auxiliary source of current connected to the field winding of each of said motors, and means for disconnecting said auxiliary source only from the field winding of the motor which is short-circuited, and for reducing the potential of the auxiliary source which remains connected to its associated field winding.

In witness whereof, we have hereunto set our hands this 15th day of March, 1916.

RAY STEARNS.
WILLIAM S. H. HAMILTON.
